GLOVE CONSTRUCTION

Scott Anderson, Champaign, Ill., assignor to
 Illinois Glove Company, a partnership com-
 posed of Samuel Shmikler, Joseph Shmikler,
 and Ray Shmikler, all of Chicago, Ill.

Application June 25, 1945, Serial No. 601,474

8 Claims. (Cl. 2—169)

1

This invention relates to an improved glove construction and particularly to a glove of the fourchette type.

In making gloves one of the big problems is to provide sufficient room in the fingers in order that the glove may be comfortably worn. Gloves in general are classified according to the manner in which this is accomplished. One such method is to insert fourchettes between the palm finger section and the back finger section of the gloves to provide the required room. This type of glove is generally referred to as the fourchette type and this invention is primarily directed toward the fourchette type of glove.

This invention is more particularly directed toward a fourchette type of glove wherein the seam is bonded by an adhesive or cement, rather than joined by stitching.

To my knowledge there is no glove on the market bonded at the seams by an adhesive although suitable cements for this purpose have long been known. One of the main reasons why no glove cemented at the seams has been marketed, is the many problems involved in the manufacture of such a glove and this invention solves one of the major problems. In joining the fourchette to the front and back sections by stitching, the type and shape of the fourchette is not important where the only problem is one of stitching around the finger tips and in between the fingers at the base to avoid buckling, wrinkling and the like around the curved portion of the fingers since the operator of a sewing machine can readily overcome this difficulty by the simple means of gathering in the fourchette at the proper places. This cannot be done where gloves are joined at the seams by a cement since such gloves are not manufactured by a device like a sewing machine. Furthermore sewing is a slow process compared with the process of making my glove as will be hereinafter fully described.

It is therefore an object of this invention to construct a fourchette in such a manner that it may be readily joined by cementing to the palm and back sections without wrinkling and buckling and which lends itself to being assembled commercially, rapidly and economically, which would not be possible if the existing type of fourchettes were used.

It is a further object of my invention to construct a glove using my type of fourchette in a continuous manner throughout as the joining strip between the front and the back portions of the glove.

It is a further object of my invention to provide

2

a reversible glove using my type of fourchette which is a major improvement in the art of making reversible gloves since it permits the use of cements for bonding the seams of the glove which was heretofore not possible. Reversible gloves have appeared on the market from time to time but they have never been successful since all used stitching in the seams. It is well known in the glove art that the stitching is the weakest portion of the glove and no matter how strong the material is, the glove quickly wears out and must be discarded since the seam is the first to wear out and therefore there has been no object in having a reversible glove since the purpose of a reversible glove is to enable the wearer to obtain more service from the glove by wearing it on either hand. By the use of my glove the seam is the strongest part of the glove and for the first time a reversible glove becomes a commercial reality. By actual test the seams on my reversible gloves are more than ten times stronger than a glove wherein the seams are stitched.

The bonding of the seams by a cement permits a less bulky seam and the bond may be made between the various sections of the glove so that it does not need to be turned after the seam is bonded. It is the present practice in making gloves that the seam is stitched inside out, which is an expensive and time consuming operation.

Any cement as long as it has good bonding properties for joining the seam may be used. Many of such cements are available on the market today. However I prefer to use a cement of the plastic type, either of the thermoplastic or the thermosetting type. Some cements require little or no heating to form a bond while others like thermoplastic materials require heating but in all cases it is usually desirable to apply heat to speed up the bonding process.

Some of the thermoplastic materials which I prefer to use because of their rapid bonding on heating include: rubber hydrochloride, vinyl resin, plasticized polyvinyl chloride, vinylidene chloride, and various cellulose derivatives such as cellulose nitrate. However, it is also within the scope of my invention to use the following thermoplastic materials: polyvinyl acetal, casein and its derivatives, cellulose acetate, polystyrene, polyvinyl acetal, ethyl cellulose, polyvinyl formal, methyl methacrylate resin, polyvinyl butyral, cellulose acetate butyrate, and vinyl chloride-acetate copolymer, etc.

Among my preferred thermosetting materials are vinyl resin formaldehyde, polyvinyl acetate emulsions, and phenol formaldehyde resins.

However, I may use any one of the following thermosetting materials; urea formaldehyde, melamine formaldehyde, phenolic furfural, etc. It is within the scope of my invention to use the above plastic materials either alone or in a mixture.

It is also within the scope of my invention to use certain plasticizers with any of the above materials such as dibutyl phthalate, tributyl phosphate, toluene sulfonamide, tricresyl phosphate, methoxyethyl phthalate, and others. Also, when it is desired to apply a coating of the plastic on the material to be bonded, various solvents may be used, such as toluol, alcohols, acetates, and the like.

In general the adhesive after forming the bond should be pliable so as to leave the seam flexible.

Thermosetting materials form a bond with other materials upon heating in the presence of a high frequency current, but thermoplastic materials after the heating step must be allowed to cool to fix the bond.

The cement may be applied in a number of ways. It may be fed into the seam in the form of a welt. However it is preferred to apply the plastic material in liquid form along the edges of the seam both on the fourchette and the front and back sections and allow to dry before assembly. Also it is within the scope of my invention to mix the cement with a suitable binder and extrude it into the seam.

Another method includes tacking a thin strip of adhesive to the edge of the material to be bonded.

The cement may be bonded in the seam by heating in any suitable manner but I prefer to use induction type of heating because it does not involve handling hot apparatus as is necessary in directly applied heating. It permits a better control by the operator during bonding particularly when forming the sharp curves required in the fabrication of gloves. Furthermore, such heating is practically instantaneous. In addition induction heating heats the material uniformly through the seam and does not subject the glove material to a higher temperature than the cement bond. The frequency of the current used to form the bond by induction heating may vary from several hundred thousand to several hundred million cycles per second depending on the material to be bonded and the type of adhesive used. In general the temperature required for bonding cements and particularly plastic cements varies from about 100° to about 250° C. As a rule, high pressures are not required to affect the bond but moderate pressures of two to 50 pounds per square inch have been used with beneficial results. Enough pressure should be applied and in such a manner as to insure the formation of uniform seams well bonded.

Various types of glove materials have been used in making my glove but my method of making a glove is particularly useful in the manufacture of cloth gloves.

In general my glove comprises a palm finger section, a back finger section and a continuous fourchette forming a seam with each section and bonded by applying a cement to the seams and heating. The fourchettes have notches around each finger tip and incisions in opposite edges at the base between the fingers which not only provides sufficient material to form a lap-type of seam but a fourchette constructed in this manner does not tend to buckle or to wrinkle when the glove is put together in a commercial

manner such as using a mold or press rather than putting it together by hand.

Other objects, advantages and uses of my invention will become apparent by referring to the drawings in which

Figure 1 illustrates in perspective one type of glove using a continuous fourchette which is made by my invention.

Figure 2 shows the type and position of the notches and incisions in the fourchette for preventing buckling and wrinkling during the construction of the glove.

Figure 3 shows a variation of the type of incision shown in Figure 2.

Figure 4 is a perspective view illustrating the manner of the over-lapping of the seams and particularly showing the type of incision illustrated in Figure 3.

Figure 5 is a perspective view of a finger which is frequently desirable having the tip of the finger tapered in two directions, one direction from front to back and one direction from side to side.

Figure 6 shows a variation in the notches from Figure 2 which is preferably used in the finger construction shown in Figure 5.

Throughout the drawings the same reference numbers will be used for comparable parts in order to make the drawings easier to follow.

Referring to the drawings, Figure 1 illustrates in perspective one type of glove which may be made by my invention. It shows a glove of the reversible type in which a palm section 1 and a back section 2 are formed to substantially the same size and shape. It should also be noted that in this type of glove the thumb may be cut as an integral part of the pattern for the front and the back sections 1 and 2; although it is possible to cut the thumb separately and add it later to form a complete glove. Although it is not necessary, it is preferable to use a continuous fourchette although each fourchette section in between the fingers and the side walls of the glove may be separate sections joined together prior to the final construction of the glove or during the construction.

Referring to Figures 1 and 2 the fourchette has notched portions corresponding to the tip of each finger and thumb as is indicated by using the same reference numbers in Figures 1 and 2. The notched portion corresponding to the little finger is indicated by the numeral 4; for the third finger by the numeral 5; for the second finger by the numeral 6; for the first finger by the numeral 7; and for the tip of the thumb by the numeral 8. Furthermore in this glove the fourchette is used throughout as the joining means between the front 1 and back section 2 and the fourchette begins at 9 and runs continuously up the side of the glove and around the fingers and ends at point 10 on the opposite side.

The particular shape of the notches and the number of the notches are relatively unimportant provided sufficient material is removed by the notches so that when that portion of the fourchette is brought around the tip of the finger, buckling or wrinkling will not result. Furthermore it is important not to have the notches extend into the fourchette to such an extent that sufficient material is not left for over-lapping of the front and back sections on to the fourchette to a distance greater than the extent of notches in order to provide sufficient material for coating with cement and for forming a good bond.

Similarly a pair of spaced incisions on oppo-

site edges of the fourchette are made for the portion of the fourchette lying at the base between the fingers. It is not necessary that any material be removed by these incisions and it is preferred that no material is removed so that the material in between the incisions can overlap on to the front and back sections to provide a bonding area as will be more fully described in connection with Figure 4. Incisions 11, 12, 13 and 14 in Figure 2 are positioned in the glove construction in Figure 1 as indicated by the same numbers.

The glove illustrated in Figures 1 and 2 was made in the following manner: The front and back sections 1 and 2 and the fourchette 3 were cut by the usual stamping machine using proper dies and the three sections 1, 2, and 3 were coated along the seam edge using a thermoplastic material. It is preferable for ease of handling to allow the thermoplastic cement to dry before assembling. The three sections were then laid in a mold and this operation involves only about 15 seconds. The glove in the mold was then heated by induction heating at a temperature around 200° for about 40 minutes. The glove was then allowed to cool in the mold for about 30 seconds and then the mold removed. It might look from the above that it takes 40 minutes to make a glove commercially but this is not the case since hundreds of these molds may be placed in the same induction furnace at one time and by the use of only one cutting machine, one assembling station and one induction furnace a glove may be turned out about every 15 seconds which in itself is a remarkable improvement over previous methods for manufacturing gloves.

A glove made in this manner by actual test has a resistance to shear of over 500 pounds per square inch which is over 10 times the shearing strength for gloves made by stitching.

Referring to Figures 3 and 4, numeral 15 in Figure 3 illustrates incisions angling towards each other and towards the center of the fourchette and is one type of incision which may be used and has the advantage of providing a strong bonding area. This is partly shown in Figure 4 by the same numbers. In Figure 4 fingers 16 and 17 constructed in the manner shown in Figure 1 have the front and back sections forming a seam area as indicated by the number 18. The spreading of the sections 15 by the incision also provides a large bonding area. A large bonding area is not necessary for a force exerted by pulling of the fingers 16 and 17 apart since the continuous fourchette itself resists that force. However a force exerted by pulling apart the front and back sections would tend to pull the seams apart if it were not for the bonding areas as indicated by the numeral 15. Therefore I have provided a construction of the glove which makes it possible to have the shearing strength heretofore mentioned.

Figure 5 is a perspective view of a finger which tapers at the tip both from front to back and from side to side and, this type of finger especially in a dress glove, is often desired. However this type of taper in the fingers makes it important to use notches of the type shown in Figure 6. The notched portion between numerals 19 and 20 must bend around the finger shown in Figure 5 between 19 and 20 so as not to form wrinkles during the glove construction. This is accomplished by first cutting the fourchette in a slow bending arc or curve between points 21 and 22 and a

hyperbola type of curve has been found best suitable for this purpose. The notches 22 are then cut in opposite sides along the slow bending curve. The notches cut in this manner eliminate all wrinkling and buckling when the glove is assembled and manufactured commercially by using molds, presses and the like where individual attention cannot be given by the operator to each finger tip as can be done if the glove were stitched.

The above description and the various embodiments of my invention are given for illustrative purpose and are not intended to limit my invention which is only limited by the following claims:

- 15 1. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 20 2. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 25 3. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 30 4. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 35 5. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 40 6. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 45 7. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 50 8. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 55 9. A glove comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 60 10. A hand covering comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 65 11. A hand covering comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 70 12. A hand covering comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.
- 75 13. A hand covering comprising a preformed palm section, a preformed back section, and a preformed fourchette, said fourchette having a plurality of V-shaped notches around the finger tips, said palm section and said back section having their marginal edges joined in overlapping manner with the marginal edges of said fourchette throughout the entire periphery of said palm and back section, a heat-responsive, plastic, water impervious bonding agent disposed between said marginal edges and constituting the sole bonding means for said marginal edges, said marginal edges being free from stitching extending therethrough.

edges at the base between the finger tips; said palm section and said back section having their marginal edges joined in over-lapping manner with the marginal edges of said fourchette throughout the entire periphery of said palm and back section; a heat-responsive, plastic, water-impervious bonding agent disposed between said marginal edges and constituting the sole bonding means for said marginal edges, said marginal edges being free from stitching extending therethrough.

6. A method of making a reversible glove comprising preforming substantially identical palm and back sections; preforming a continuous fourchette having a plurality of V-shaped notches around the finger tips, placing a heat-responsive, plastic, water-impervious bonding agent along the marginal edges of said palm and back sections and said fourchette; overlapping the marginal edges of said palm and back sections on said marginal edges of said fourchette such that both said palm and back sections overlap the fourchette on the outside of the glove; and then bonding said marginal edges by heating.

7. A method of making a reversible glove comprising preforming substantially identical palm and back sections; preforming a continuous fourchette having incisions on opposite edges at the base between the finger tips; placing a heat-responsive, plastic, water-impervious bonding agent along the marginal edges of said palm and back sections and said fourchette; overlapping the

marginal edges of said palm and back sections on said marginal edges of said fourchette such that both said palm and back sections overlap the fourchette on the outside of the glove; and then bonding said marginal edges by heating.

8. A method of making a reversible glove comprising preforming substantially identical palm and back sections; preforming a continuous fourchette having a plurality of V-shaped notches around the finger tips and incisions on opposite edges at the base between the fingers; placing a heat-responsive, plastic, water-impervious bonding agent along the marginal edges of said palm and back sections and said fourchette; overlapping the marginal edges of said palm and back sections on said marginal edges of said fourchette such that both said palm and back sections overlap the fourchette on the outside of the glove; and then bonding said marginal edges by heating.
